(57) **CLAIM**

The ornamental design for a hair drier, as shown and described.

DESCRIPTION

FIG. 1 is a front elevational view of a hair drier showing our design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof;

FIG. 8 is a second perspective view thereof; and,

FIG. 9 is a used state view thereof.

The broken lines shown in the drawings depict portions of the hair drier that form no part of the claimed design. The additional broken lines shown in FIG. 9 are included for the purpose of showing environment that forms no part of the claimed design.

1 Claim, 7 Drawing Sheets
